UNITED STATES PATENT OFFICE.

ERLING SARJENT, OF KINGFISHER, OKLAHOMA.

ENGINE.

1,350,570.

Specification of Letters Patent. Patented Aug. 24, 1920.

Application filed July 29, 1919. Serial No. 313,965.

To all whom it may concern:

Be it known that I, ERLING SARJENT, a citizen of the United States, and a resident of Kingfisher, in the county of Kingfisher 5 and State of Oklahoma, have invented a new and Improved Engine, of which the following is a full, clear, and exact description.

This invention relates to improvements in engines, and more particularly to a compound engine in which the otherwise waste gases are utilized to drive an expansion engine, which latter may also be utilized as a starting means for the internal combustion engine.

15 A further object is to provide an engine of the character stated in which a gas receiver is interposed between the internal combustion engine and the expansion engine, and a portion of the exploded gases from 20 the internal combustion engine is admitted and stored in the receiver and supplied to the expansion engine as desired, the supply being under control.

With these and other objects in view the 25 invention consists in certain novel features of construction, and combinations and arrangements of parts, as will be more fully hereinafter described and pointed out in the claims.

30 The accompanying drawing is a sectional plan view illustrating my improvements.

1 represents a cylinder of an internal combustion engine. While I have illustrated the same of the ordinary type for exploding 35 an air and gas mixture, it is, of course, to be understood that instead of the same I might employ any ordinary form of the Diesel or similar type, in which oil is supplied to the cylinder and mixed with the air to be burned 40 therein.

The cylinder 1 is provided with a piston 2 having a connecting rod 3 connecting the same with a crank disk 4 on a drive shaft 5. 6 represents a cylinder of the ordinary 45 type of expansion engine having a reciprocating piston 7 therein connected by a rod 8 with a crank disk 9 on the drive shaft 5. The cylinder 6 is provided with the ordinary valve chest 10 having a slide valve 11 therein 50 connected by a rod 12 with an eccentric 13 on shaft 5, the latter having an ordinary fly wheel 14 fixed thereto.

55 The cylinder 1 is provided with an intake valve 16 and an exhaust valve 15 operated in any approved manner, and a primary exhaust port 17 is provided in the wall of the

cylinder and is opened by the piston 2 as the latter reaches the extreme of its power stroke. This port 17 is normally closed by a valve 18 having a coiled spring 19 exerting 60 the necessary pressure thereon.

The port 17 is connected by a pipe 20 with a gas receiver 21 and the latter is connected by a pipe 22 with the valve chest 10, a suitable cock 23 being located in the pipe 22. 65

The operation is as follows: On the power stroke of piston 2, when the latter uncovers the port 17, if the pressure in cylinder 1 is greater than in container 21, the valve 18 will be opened so that a portion of the exhaust will escape through the port 17 into the container 21. 70

It is a well known fact that in the great majority of cases, the gases are only partially burned and the greater portion of such unburned gases is adjacent the piston, hence by locating the port 17 as indicated, I am enabled to recover this unburned portion of the gas and store the same in the container 21. The port 17 will be long enough for all practical purposes and will be cut off by the piston 2 when the latter begins its exhaust stroke so that the valve 18 can readily close. 80

The gas in container 21 is admitted to the valve chest 10 and operates the piston 7 by its expansion force at both ends of the cylinder 6, as will be readily understood. The cock 23 is normally opened and may be closed when it is desired to stop the engine. The container 21 will have therein a sufficient quantity of gas under pressure to operate the piston 7 and start the engine, hence doing away with the necessity for other means for turning over the piston of the explosion cylinder. 90

95 It is apparent that the size and number of ports 17 can be varied as desired, and a wide range of modification might be resorted to in the apparatus without departing from my invention, hence I do not limit myself to the precise details set forth but consider myself at liberty to make such changes and alterations as fairly fall within the spirit and scope of the appended claims.

I claim:

1. The combination with an expansion engine, and an internal combustion engine, of a gas container located between the engines, a pipe connecting the container with the valve chest of the expansion engine, said internal combustion engine having a port in its wall constituting a valve seat and located at a 110

- point which will be uncovered by the piston of the internal combustion engine as the latter reaches the end of its power stroke, a valve casing at the side of the cylinder enclosing the said port, a valve in said port, and a pipe connecting the tank with said valve casing, whereby the pressure of gas in the casing operates to maintain the valve in closed position.
- 5 2. The combination with an expansion engine, and an internal combustion engine, of a gas container located between the engines, a pipe connecting the container with the valve chest of the expansion engine, said internal combustion engine having a port in its wall constituting a valve seat and located

at a point which will be uncovered by the piston of the internal combustion engine as the latter reaches the end of its power stroke, a valve casing at the side of the cylinder enclosing the said port, a valve in said port, a pipe connecting the tank with said valve casing, whereby the pressure of gas in the casing operates to maintain the valve in closed position, a spring casing located on 20 the valve casing, a stem on the valve projecting into the spring casing, and a spring around the stem in the spring casing exerting pressure on the valve tending to close the same.

ERLING SARJENT.
